United States Patent Office.

LEVI W. SWAFFORD, EDWARD BUTLER, AND JOHN R. HESS, OF MUSCATINE, IOWA.

Letters Patent No. 83,421, dated October 27, 1868.

IMPROVEMENT IN BLIND-SLAT OPERATORS.

The Schedule referred to in these Letters Patent and making part of the same.

To all whom it may concern:

Be it known that we, LEVI W. SWAFFORD, EDWARD BUTLER, and JOHN R. HESS, of Muscatine, in the county of Muscatine, and State of Iowa, have invented a new and improved Method of Operating Window-Blinds; and we do hereby declare that the following is a full, clear, and exact description thereof, which will enable others skilled in the art to make and use the same, reference being had to the accompanying drawings, forming part of this specification.

This invention relates to a new and improved method of operating and adjusting the slats of window-blinds.

In the accompanying plate of drawings—

Figure 1 is a view of the side of the window-casing, with the blind open, showing our invention in position thereon.

Figure 2 is a plan view of the bottom of the window-casing, showing the device for fastening the blind.

Figure 3 is a front view of a portion of the blind, showing the device for adjusting the movable slats.

Similar letters of reference indicate corresponding parts.

The blind, A, is constructed and secured to the casing B by hinges, in the ordinary way, as shown.

Upon the hinge-edge of the blind, A, near the bottom, is secured a metallic attachment, C, semi-cylindrical in form, having a spiral slot or thread in the same, as shown in the drawing, said slot extending, from near the bottom of said attachment, upward and around the same.

Said slot is of sufficient depth to receive a ball on the end of the lever D, and is wider within than without, being only of sufficient width at the outside to permit the neck of the lever D to which said ball is attached to move freely within the same.

To the same side of the casing B to which the blind, A, is hinged, is pivoted a metallic lever, D.

The lever D is of sufficient length to permit of a forward and backward movement to open and close the blinds A, and is provided with a slot of sufficient length for said backward and forward movement on the pivot b, by means of which the lever D is pivoted to the casing B.

Near the front end of the lever D, the slots in the same are enlarged, as shown, so as to drop upon the pivot b, to hold the blind open.

Two upright strips a a', provided with slots to receive the levers D and E, are secured to the casing B, to hold said levers against said casing B.

Upon the bottom of the casing B, and near the opposite side of the same to the lever D, is pivoted a horizontal lever, E, as shown, said lever E' being provided with a suitable handle at one end, by means of which said lever is moved into and out from the slot in the blind, B, and is bent upward at the other end so as to engage in a slot in the lower corner of the blind, A, by means of which the blind is secured when shut, additional security being given by a hook, e', which, engaging with the handle of the lever E', prevents said lever E from moving.

Upon the edge of the lower movable slat of the blind, A, is secured a bent metallic arm, G, projecting over the frame of the blind, A, to the edge of the same on the hinge-side of the blind, A.

Upon the same side of the casing B as the lever D, and directly under the same, is a short metallic lever, E, pivoted to said casing B by a pivot through a slot in the said lever E, as shown in the drawing; and so as that the one end of said lever may be placed over or under the projection on the arm G, by means of which the slats of the blind, A, are adjusted.

The ends of the levers D, E, and E', are within the windows in the casing B, and so as that the blind, A, and the slats of the same, may be operated without opening the windows.

The operation is such, the blind, A, being closed, that by moving the lever E' in one direction, the blind is released, when, by pressing the lever D backward and downward, the blind, A, is opened, and by the reverse movement of said levers D and E', said blind, A, is closed and fastened, the slats of the blinds being adjusted in any position by the lever E.

We claim as new, and desire to secure by Letters Patent—

The bent arm G and slotted lever E, arranged, with relation to the blind-slats and window-casing, in such a manner that their combined action shall adjust said blind-slats in any required position, as herein shown and described.

The above specification of our invention signed by us, this 5th day of December, 1867.

LEVI W. SWAFFORD.
EDWARD BUTLER.
JOHN R. HESS.
